UNITED STATES PATENT OFFICE

105,177

DESIGN FOR A DRESS

Sally Moser, New York, N. Y.

Application April 19, 1937, Serial No. 68,858

Term of patent 3½ years

To all whom it may concern:

Be it known that I, Sally Moser, a citizen of the Union of Soviet Socialist Republics, residing in the city and State of New York, have invented a new, original, and ornamental Design for a Dress, of which the following is a specification, reference being had to the accompanying drawing, constituting a part thereof.

Figure 1 is a front view of the dress.

Figure 2 is a rear view of the dress as shown in Figure 1.

The characteristic feature of my design resides in the combination on the dress disclosed, of a net blouse of the instant configuration, embroidered as shown and in association with a multi-pleated skirt.

I claim:

The ornamental design for a dress, substantially as shown and described.

SALLY MOSER.
